MACHINE FOR MAKING CANS

Harry Sebell, Boston, Mass., assignor of one-half
to Arthur H. Parker, Lexington, Mass.

Application August 29, 1936, Serial No. 98,478

2 Claims. (Cl. 113—23)

Some cans are made with a body section to which the can bottom is secured and a neck section which is formed with a closure-receiving opening and which is secured to the upper end 5 of the body section either by means of a double-lock seam or by a crimping operation followed by a soldering operation. The machines used for seaming or crimping the neck section to the body section usually have a chuck member insertable 10 into the can body and forming a backing for the body and neck section while the seaming roll or the crimping roll, as the case may be, is performing its operation.

During the seaming or crimping operation the 15 seaming roll or crimping roll is applying considerable lateral pressure against the can, and one object of my present invention is to provide a novel manner of supporting the chuck so as to enable it to resist such lateral pressure without 20 yielding.

In order to give an understanding of the invention, I have illustrated in the drawing a selected embodiment thereof which will now be described after which the novel features will be 25 pointed out in the appended claims.

In the drawing;

Fig. 1 is a fragmentary sectional view illustrating a seaming machine embodying my invention;

Fig. 2 is a side view of the seaming machine on a smaller scale showing the chuck in retracted position;

Fig. 3 is a fragmentary view showing the invention as applied to a chuck for a crimping machine.

As stated above, the present improvements are capable of use in either a seaming machine designed for forming the double-lock seam by which the neck section and body section of a can are united, or a crimping machine by which the neck section and body section of a can can be crimped together preparatory to a soldering operation. In Fig. 1, wherein the invention is shown as applied to a can seaming machine, there is shown a partially-formed can of the type illustrated in my co-pending application Serial No. 48,477, filed November 6, 1935, and which comprises the body section 1 and the conical-shaped neck section 2 which is provided with a discharge opening 3 of reduced size. The body section 1 is formed with an outwardly-extending seaming flange 4 and the neck section 2 is provided with a mating seaming flange 5. The uniting of the neck section 2 to the body section 1 consists in rolling the mating flanges 4 and 5

into a double-lock seam as illustrated in said co-pending application Serial No. 48,477, filed November 6, 1935. This rolling of the seaming flanges 4 and 5 into the double-lock seam is accomplished through the medium of a chuck 6 5 adapted to fit within the body section 1 and neck section 2 of the can, and a seaming roll 7 which rolls around the mating flanges and through which radial inward pressure is applied to the flanges for rolling them into the double-lock 10 seam.

The chuck 6 is shown as having a cylindrical body portion 8 to fit within the can body and the conical neck portion 9 to fit within the conical neck section 2. This chuck is shown as secured to a shaft 10 supported in suitable bearings 11, said shaft being constructed to have an axial movement through the bearings as well as a rotary movement therein. The shaft 10 may be rotated by any suitable means (not shown) and 20 as it rotates the seaming roll 7 is pressed against the mating flanges to perform the seaming operation as usual in machines of this type.

During the rolling of the mating flanges 4 and 5 into the double-lock seam the seaming roll is 25 applying considerable pressure laterally against the seaming flanges, and in order to steady the upper end of the chuck and to enable it to resist such lateral pressure, I provide a bearing or supporting member 12 which is provided with 30 an extension 13 adapted to extend through the opening 3 in the neck section and to be received in a recess 14 with which the conical portion 9 of the chuck is provided. The bearing member 12 is shown as rotatably mounted in a suitable 35 bearing 15 which prevents any lateral movement of the bearing member 12 during the seam-forming operation. An advantage of the construction herein shown wherein the steady rest or supporting bearing 12 extends through the discharge opening of the can and has direct engagement with the chuck 6 is that no part of the steady rest engages the exterior of the neck section of the can and, therefore, there is nothing to mar or injure the exterior surface of the 45 neck section of the can during the seaming operation.

I have stated above that the shaft 10 is capable of moving axially in the bearing 11 as well as rotating therein. In using the device the shaft 50 10 will be moved axially to separate the chuck member from the bearing member 12, as shown in full lines Fig. 2, sufficiently to enable the assembled body section 1 and neck section 2 of the can to be placed over the chuck member, 55

this being done before the can bottom is attached to the body section. The shaft 10 and chuck 8 are then moved axially toward the bearing member 12 until the extension 13 of the bearing member passes through the discharge opening 3 of the neck section and into the recess 14 as shown in Fig. 1 and in dotted lines, Fig. 2. This will bring the seaming flanges 4 and 5 into position to be acted upon by the seaming roll 7 and the seaming operation is then performed. As the lateral pressure is applied to the seaming flanges through the seaming roll 7, the bearing member 12 steadies the upper end of the chuck member and prevents it from giving or yielding laterally due to the pressure of the seaming roll against the seaming flanges. It will be noted that the supporting bearing 15 is closely adjacent the extension 13 of the member 12 so that the chuck 6 has a firm support against lateral pressure closely adjacent to the point where the lateral pressure is applied.

After the seaming flanges 4 and 5 have been rolled into the double-lock seam, then the shaft 10 and chuck 6 are again retracted or lowered 25 into the position shown in Fig. 2 so as to permit the can body to be removed from the chuck.

In Fig. 3 I have shown the invention as it might be applied to a crimping machine, which is a machine by which the lower end of the neck section and the upper end of the body section are connected by a crimping rather than a seaming operation. In this embodiment the body section of the can is shown at 16 and the neck section at 17, said sections having the overlapping portions 18, 19 which are to be crimped together. 20 indicates the chuck which is inserted into the body section and neck section from the bottom of the can and which forms a backing for the overlapping portions 18, 19 where they are acted upon by the crimping roll 21. In this embodiment also the chuck 20 has a recess 14 at its end adapted to receive the extension 13 of the bearing member 12 which is inserted into the recess through the opening 3 in the end of the neck section. The bearing member 12 thus steadies and supports the portion of the chuck member against which the lateral pressure is applied so that said chuck member will be prevented from lateral yielding movement due to such pressure. In this embodiment of the invention also there is no part of the steady rest or supporting bearing which engages the exterior of the neck of the can and thus there is nothing to mar or injure in any way the exterior surface of said neck section during the seaming operation.

While I have herein illustrated the invention as applied to a chuck designed to make a can having a conical neck section, yet the invention is equally applicable to the making of cans having neck sections of other shapes. 5

I claim:

1. A machine for uniting a body section of a can to a neck section having a discharge opening by seaming together mating seaming flanges on the body section and neck section respectively, said machine comprising a chuck member having a body portion to fit within the body section of the can and a neck portion to fit within the neck section, a supporting shaft secured to one end of the body portion and by 15 which it is rotated, a rotary supporting bearing directly engaging the neck portion of the chuck member through the discharge opening of the neck section of the can, and a seaming wheel cooperating with the chuck to deform the 20 mating flanges of the neck section and the body section by applying pressure thereto in a direction transversely to the axis of the chuck thereby seaming said flanges together, said rotary supporting bearing rotating with and steadyng 25 the neck portion of the chuck member and preventing yielding movement thereof in a radial direction due to the seam-forming operation.

2. A machine for uniting the body section of a can to a conical neck section which has a discharge opening by seaming together mating seaming flanges on the body section and neck section respectively, said machine comprising a rotary chuck member having a body portion to fit the body section of the can and a conical 35 neck portion to fit the conical neck section of said can, said conical neck portion of the chuck having a recess in its smaller end in alignment with the discharge opening in the neck section of the can, a rotary shaft rigid with the body portion of the chuck member and by which it is rotated, a rotary supporting member having an end portion of a size to enter the opening in the neck section of the can and to fit the recess in the chuck, a bearing in which said supporting 40 member is rotatably mounted, and a seaming roll cooperating with the chuck member to deform the mating seaming flanges of the neck section and body section by applying pressure thereto in a direction transverse to the axis of the chuck thereby to seam said flanges together, said supporting member providing a support for the conical neck portion of the chuck which prevents lateral deflection thereof during the seam-forming operation. 45 50 55

HARRY SEBELL.
